(57) **CLAIM**

The ornamental design for a push button for switch, as shown and described.

DESCRIPTION

FIG. 1 is a front, top, and right side perspective view of a push button for switch showing my new design;

FIG. 2 is a front view thereof, a rear view being a mirror image thereof;

FIG. 3 is a left side view thereof, a right side view being a mirror image thereof;

FIG. 4 is a top view thereof; and,

FIG. 5 is a bottom view thereof.

The dashed broken lines in the figures show portions of the push button for switch that form no part of the claimed design.
